UNITED STATES PATENT OFFICE.

LEO J. SCHAEDEL, OF PITTSBURGH, PENNSYLVANIA.

DESUPERHEATER.

1,420,344.

Specification of Letters Patent. Patented June 20, 1922.

Application filed January 23, 1920. Serial No. 353,512.

To all whom it may concern:

Be it known that I, LEO J. SCHAEDEL, a citizen of the United States, residing at Pittsburgh, in the county of Allegheny and 5 State of Pennsylvania, have invented new and useful Improvements in Desuperheaters, of which the following is a specification.

The principal object of this invention is to permit a steam boiler plant furnishing superheated steam to deliver superheated steam to one type of steam engine, such as a high pressure turbine, and saturated steam to a type of steam engine or other device requiring such kind of steam for its operation. This invention is particularly useful where an industrial plant contains old types of steam engines operable by saturated steam and where it is desired to install modern types of steam engines operable 15 by superheated steam. In this combination a single boiler plant can supply superheated steam, a part of which may be saturated for use in the old types of engines, whose replacement owing to their high cost cannot 20 be replaced by units using superheated steam without heavy financial losses.

Referring to the accompanying drawing, Fig. 1 shows a central vertical section of my invention, some parts being in elevation, and 30 Fig. 2 shows a section of the valve 25 and adjacent parts. I show a desuperheater having two vertical chambers or drums 1 and 2 preferably in axial alinement and of circular cross-sections. The drum 1 is tapered downwardly as shown at 3, its lower contracted end opening into a tubular connector 4 of restricted cross-area, which connector is attached at opposite ends to the drums 1 and 2 and constitutes a means of 35 communication between their interiors. Each drum constitutes together with its internal structure a steam separator.

The upper end of the drum 1 has the contracted outlet 5 to be connected to drive a 45 steam-turbine or other engine employing superheated steam. Superheated steam is supplied to the drum 1 by the inlet pipe 6 attached, for example, to the middle of one side of the drum, which has the inlet opening 7 in line with the pipe 6. The opening 7 has fitted therein a short tube 8 extending toward the center of the drum and provided at its inner end with the downwardly-turned elbow 9 having the center of its mouth or 50 lower end at the axial center of the drum. Within the drum 1 and directly below the

elbow 9 is the conical baffle 10 having its apex or axial center arranged in line with the vertical center line of the drawing 1 and the mouth of the elbow 9. There is an 60 annular passage 11 between the drum and the periphery of the baffle.

Within the drum 2 and near the upper end thereof is the collecting conical baffle 12 having its apex directed downwardly and 65 lying in the vertical center line of the drum and the connector 4. There is an annular passage 13 between the drum 2 and the periphery of the baffle. From the apex of the baffle 12 there extends downwardly a small 70 drain pipe 14. Beneath the baffle 12 is a second downwardly-tapering or conical baffle 15 having its periphery connected to the drum 2 and its lower end truncated and extended downwardly by the vertical center 75 pipe 16 which is preferably considerably larger than the nozzle opening 23. Below the center pipe there is a conical baffle 17 having its apex extending upwards and in the center line of the center pipe 16. The 80 drum 2 has the outlet 18 for saturated steam connected thereto between the baffles 15 and 17. The condensate from the steam collects in the drum 2 below the baffle 17 and may be drawn off in any suitable manner, 85 for example, by steam traps (not shown) connected to the nipple or short tubes 19 connected to the outlet pipe 20. The water gage 21 of usual construction shows the level of the water or condensate therein. 90

22 is a downwardly directed spraying-head arranged directly and centrally below the outlet or nozzle 23 at the bottom of the drum 1. The spraying head 22 is connected by the pipe 24 with a supply of water preferably under high pressure. In this pipe is a thermostatic valve 25 or other water controlled by heat. Steam from the outlet 18 is supplied to the thermostatic element 30 of the valve 25 through the pipe 26 and 100 returned by the pipe 27. The element 30 may be an accordion-shaped vessel containing a liquid which is changed to gas when heated to a sufficient temperature. The gas pressure in the element 30 elongates the latter and pushes up the valve stem 31, thereby causing the valve proper 32 to be raised from its seat. The element 30 is in a chamber 34 separated from the chamber 35 for the water passing through the valve seat and 105 into the pipe 24. The element 30 may be of any expansive type. The one described is 110

extensively used with radiators of automobiles and therefore needs no extended description. 28 is a thermometer in the outlet 18 to enable the operator to learn if the 5 temperature is such as to obtain the required degree of steam saturation.

The drums are provided with the manholes 28', and the connector 4 is provided opposite the spraying head 22 with an inspection window covered by the hand-plate 29.

The operation of the described invention is as follows: Superheated steam enters the upper separator at the inlet 6 and traverses the pipe 8 and elbow 9. The steam issuing 15 from the elbow 9 impinges on the baffle 10 and takes two courses. One part of it passes in its superheated, or relatively dry, condition through the outlet 5 to the steam engine or engines or other apparatus requiring superheated steam. Another part of the steam 20 after passing over the baffle 10 continues downwards through the annular passage 11, along the tapered wall 3, and then through the contracted nozzle opening 23 and down 25 the connector 4. The steam increases its velocity along the wall 3 and issues at high velocity from the nozzle 23 and, in case the valve 32 is open, it picks up the spray from the head 22, the spray and the steam intermingling. From the connector 4 the steam 30 and watery vapor are discharged or dashed into the collecting baffle 12 where the steam and vapor are more thoroughly mixed and atomized. The steam and vapor then move 35 up over the baffle 12 and escape through the annular passage 13 with their velocity again increased, whereby they pick up more moisture owing to the increased velocity. The mingled steam and vapor pass on downward, the baffle 15 bringing them to the central pipe 16, which directs them in an expanding condition against the baffle 17. During the travel of the steam downwardly the water has become thoroughly atomized, due 40 to their expansion, contraction, and changes in velocity. The steam now thoroughly saturated passes from the lower separator through the outlet 18 to any suitable apparatus using saturated steam. At the baffle 45 17 just before the steam passes out of the separator, any excess of water in the steam is diverted downwardly into the bottom of the lower separator.

If the steam passing through the pipe 26 50 to the thermostatic element 23 of the valve 25 has the temperature corresponding to the desired degree of steam saturation (the thermostat being set to open the valve if the temperature of its actuating element is above 55 that required for said degree of saturation), the valve 32 remains closed; but, if the temperature of the steam passing through the outlet 18 rises above that corresponding to the desired degree of saturation, the hotter 60 steam traversing the pipe 26 causes the oper-

ation of the valve 32 and the discharging of water spray from the head 22 into the connector 4. Here the steam picks up the spray which causes its temperature to fall. When the steam has become saturated to the said 70 degree, the cooler steam from the pipe 26 causes the valve 32 to close. The opening and closing of the valve 25 occurs automatically as the steam is below saturation or at saturation. 75

Modifications of my invention may be made without sacrificing the principles thereof.

I claim:

1. The combination of a drum, means for admitting superheated steam into the same, outlet means leading a portion of the superheated steam from the drum, a second drum communicating with the first drum, means for increasing the velocity of a portion of 80 the steam at some period of its travel from the first drum to the second drum, means for admitting water into the steam during its increased velocity, and means, depending upon the degree of saturation of the steam 85 in the second drum, for admitting water to the last named means when the saturation is below a predetermined degree and cutting off the water when the saturation is of said degree. 90

2. The combination of a drum, means for admitting superheated steam into the same, outlet means leading a portion of the superheated steam from the drum, means for projecting the steam away from the said outlet means, a second drum communicating with the first drum, means for increasing the velocity of a portion of the steam at some period of its travel from the first drum to the second drum, means for admitting water into the steam during its increased 100 velocity, and means, depending upon the degree of saturation of the steam in the second drum, for admitting water to the last named means when the saturation is below a predetermined degree and cutting off the water when the saturation is of said degree. 105

3. The combination of a drum, means for admitting superheated steam into the same, outlet means leading a portion of the superheated steam from the drum, a second drum communicating with the first drum, a contracted nozzle for increasing the velocity of a portion of the steam at some period of its travel from the first drum to the second 115 drum, means for admitting water into the steam during its increased velocity, and means, depending upon the degree of saturation of the steam in the second drum, for admitting water to the last named means when the saturation is below a predetermined degree and cutting off the water when the saturation is of said degree. 120

4. The combination of a drum, means for admitting superheated steam into the same, 125

- outlet means leading a portion of the superheated steam from the drum, a second drum communicating with the first drum, means for increasing the velocity of a portion of the steam at some period of its travel from the first drum to the second drum, said last means comprising a passage tapering toward the second drum, means for admitting water into the steam during its increased velocity, and means, depending upon the degree of saturation of the steam in the second drum, for admitting water to the last named means when the saturation is below a predetermined degree and cutting off the water when the saturation is of said degree. 5
5. The combination of a drum, means for admitting superheated steam into the same, outlet means leading a portion of the superheated steam from the drum, means for projecting the steam away from the said outlet means, a second drum communicating with the first drum, a baffle for spreading the projected steam, a second drum communicating with the first drum, means for increasing the velocity of a portion of the steam at some period of its travel from the first drum to the second drum, means for admitting water into the steam during its increased velocity, and means, depending upon the degree of saturation of the steam in the second drum, for admitting water to the last named means when the saturation is below a predetermined degree and cutting off the water when the saturation is of said degree. 10
- 30 6. The combination of a drum, means for admitting superheated steam into the same, outlet means leading a portion of the superheated steam from the drum, a second drum communicating with the first drum, means for increasing the velocity of a portion of the steam at some period of its travel from the first drum to the second drum, means for admitting water in the form of spray into the steam during its increased velocity, and means, depending upon the degree of saturation of the steam in the second drum, for admitting water to the last named means when the saturation is below a predetermined degree and cutting off the water when the saturation is of said degree. 15
- 40 7. The combination of a drum, means for admitting superheated steam into the same, outlet means leading a portion of the superheated steam from the drum, a second drum communicating with the first drum, means for increasing the velocity of a portion of the steam at some period of its travel from the first drum to the second drum, means for admitting water into the steam during its increased velocity, means causing the water in the steam to become more finely subdivided and more intimately mixed with the steam, and means, depending upon the degree of saturation of the steam in the second drum, for admitting water to the last named means when the saturation is below a predetermined degree and cutting off the water when the saturation is of said degree. 20
- 45 8. The combination of a drum, means for admitting superheated steam into the same, outlet means leading a portion of the superheated steam from the drum, a second drum communicating with the first drum, means for increasing the velocity of a portion of the steam at some period of its travel from the first drum to the second drum, means for admitting water into the steam during its increased velocity, a baffle in the path of the watered steam, and means, depending upon the degree of saturation of the steam in the second drum, for admitting water to the last named means when the saturation is below a predetermined degree and cutting off the water when the saturation is of said degree. 25
- 50 9. The combination of a drum, means for admitting superheated steam into the same, outlet means leading a portion of the superheated steam from the drum, a second drum communicating with the first drum, means for increasing the velocity of a portion of the steam at some period of its travel from the first drum to the second drum, means for admitting water into the steam during its increased velocity, a dished collecting baffle arranged in the path of the watered steam, and means, depending upon the degree of saturation of the steam in the second drum, for admitting water to the last named means when the saturation is below a predetermined degree and cutting off the water when the saturation is of said degree. 30
- 55 10. The combination of a drum, means for admitting superheated steam into the same, outlet means leading a portion of the superheated steam from the drum, a second drum communicating with the first drum, means for increasing the velocity of a portion of the steam at some period of its travel from the first drum to the second drum, means for admitting water into the steam during its increased velocity, a dished collecting baffle arranged in the path of the watered steam spaced from the wall of the second drum so as to create an annular passage for the steam passing from the collecting baffle, and means, depending upon the degree of saturation of the steam in the second drum, for admitting water to the last named means when the saturation is below a predetermined degree and cutting off the water when the saturation is of said degree. 35
- 60 11. The combination of a drum, means for admitting superheated steam into the same, outlet means leading a portion of the superheated steam from the drum, a second drum communicating with the first drum, means for increasing the velocity of a portion of the steam at some period of its travel from the first drum to the second drum, means for admitting water into the steam during its increased velocity, means causing the water in the steam to become more finely subdivided and more intimately mixed with the steam, and means, depending upon the degree of saturation of the steam in the second drum, for admitting water to the last named means when the saturation is below a predetermined degree and cutting off the water when the saturation is of said degree. 40

admitting water into the steam during its increased velocity, a baffle arranged to spread the watered steam, a second baffle beyond the said baffle to contract the said steam, and 5 means, depending upon the degree of saturation of the steam in the second drum, for admitting water to the last named means when the saturation is below a predetermined degree and cutting off the water when 10 the saturation is of said degree.

12. The combination of a drum, means for admitting superheated steam into the same, outlet means leading a portion of the superheated steam from the drum, a second drum 15 communicating with the first drum, means for increasing the velocity of a portion of the steam at some period of its travel from the first drum to the second drum, means

for admitting water into the steam during its increased velocity, a baffle arranged to 20 spread the watered steam, a second baffle beyond the said baffle to contract the said steam, an outlet for the steam in the second drum, a third baffle in the second drum to intercept the steam after it leaves the second baffle and before it reaches the outlet, and means, depending upon the degree of 25 saturation of the steam in the second drum, for admitting water to the last named means when the saturation is below a predetermined degree and cutting off the water when 30 the saturation is of said degree.

Signed at Pittsburgh, Pa., this 19th day of January, 1920.

LEO J. SCHÄEDLE.
